UNITED STATES PATENT OFFICE

126,551

DESIGN FOR A DOOR PULL OR THE LIKE

Earl Borchers, Rockford, Ill., assignor to American Cabinet Hardware Corporation, Rockford, Ill., a corporation of Illinois

Application January 31, 1941, Serial No. 98,605

Term of patent 7 years

To all whom it may concern:

Be it known that I, Earl Borchers, a citizen of the United States, residing at Rockford, in the county of Winnebago and State of Illinois, have invented a new, original, and ornamental Design for a Door Pull or the like, of which the following is a specification, reference being had to the accompanying drawing, forming a part thereof.

Fig. 2 is a front view of the pull shown in Fig. 1.
Fig. 3 is a side view of the pull shown in Fig. 1.

I claim:

The ornamental design for a door pull or the like, substantially as shown.

EARL BORCHERS.
